UNITED STATES PATENT OFFICE.

FREDERIC W. BITTMAN, OF ST. LOUIS, MISSOURI.

DESIGN FOR A SIGHT-FEED CYLINDER-LUBRICATOR.

SPECIFICATION forming part of Design No. 30,593, dated April 18, 1899.

Application filed June 17, 1898. Serial No. 683,757. Term of patent 14 years.

To all whom it may concern:

Be it known that I, FREDERIC W. BITTMAN, a citizen of the United States, residing at the city of St. Louis, in the State of Missouri, have 5 invented and produced a new and original Design for a Sight-Feed Cylinder-Lubricator, of which the following is such a full, clear, and exact description as will enable any one skilled in the art to which it appertains to 10 make and use the same, reference being had to the accompanying drawings, forming part of this specification.

In the accompanying drawings, where my new and original design is shown and where 15 like marks of reference refer to the same parts, Figure 1 is a front elevation, and Fig. 2 is a side elevation.

I will now describe the leading features of my design. 20 5 and 6 are two rectangular portions, which are connected at opposite sides by arms 7. Extending upwardly from the rectangular part 5 is a cylindrical portion 8, and extending downwardly from the part 6 is a similar 25 cylindrical portion 9. At the bottom of the cylindrical portion 9 is an enlarged portion or flange 10. Extending downwardly from

the enlarged portion 10 is a cylindrical portion 11, and projecting downwardly from the cylindrical portion 11 is a cylindrical portion 12 of smaller diameter than the said portion 11. The cylindrical part 12 is provided with a nut 13. Extending upwardly from the part 6 is a cylindrical portion 14, and extending downwardly from the part 5 is a similar cylindrical portion 15. The parts 14 and 15 are provided with nuts 16. Extending from the front of the part 6 is a boss 17. Extending downwardly from the part 12 is a rod or stem 18, provided with a head 19. Projecting rearwardly from the cylindrical part 9 is a cylindrical part 20.

Having fully described my invention, what I claim is new, and desire to secure by Letters Patent of the United States, is—

The design for sight-feed cylinder-lubricator substantially as shown and described.

In testimony whereof I have hereunto set my hand and seal in the presence of two subscribing witnesses.

FREDERIC W. BITTMAN. [I. S.]
